TIME SETTING DEVICE

Raymond D. Smith, Pleasantville, N. Y.

Application December 24, 1930, Serial No. 504,532

25 Claims. (Cl. 200—36)

This invention relates to means peculiarly adapted, though not limited, to association with the regular hands and face of a time telling clock for the purpose of performing a self-evident and easily understood and easily accomplished setting of one, two or more times at which the running of the clock shall produce some automatic effect such as to open or close an electric switch, a valve, light or extinguish lights, ring audible signals, cause the tripping of mechanism, or any other desired effect whatsoever.

To illustrate the principles underlying the invention I have herein chosen to illustrate a time setting device capable of determining two selective times at which automatic actions will take place such, for instance, as to alternately open or close an electric switch or a valve, which switch or valve will thereby be caused to remain open for one period and closed for another period. Obviously, the face of the clock could as well be marked to represent twenty-four hours around the entire circle or any other desired system for graduating periods of time.

In the use of "On" and "Off" automatic time switches and valves for controlling, say, the cooking of food on domestic ranges utilizing either electricity or gas for fuel it has proven to be a material factor in the commercial success of such controls that they be of a nature simple and easy to be understood and operated by women in the home and by salesmen endeavoring to sell the consumer public in general and the failure to achieve a sufficiently simple and easily understood and easily remembered means of setting the time for the cooking to start and stop in the forms of mechanism for this purpose heretofore available has been a serious obstacle to the popularizing of this otherwise desirable idea of the automatic time controlled cooking of food in the home. It has heretofore been proposed in association with the hands and face of the ordinary clock to provide two separate auxiliary time dials similar to the single dial by which the alarm is set to go off in an ordinary alarm clock but the use of same has proven confusing in the matter of sequence and the relation of setting of separate on and off hands working respectively with each of said auxiliary dials and there has been no readily visible indication of the spread of time which represents the cooking period as distinguished from the period of time during which the range shall not be in operation.

Broadly my present improvement aims to pro-

vide a means for setting time for purposes analogous to the above and for any other to which a time controlled switch or mechanism can have useful application which shall be not only self-evident as to the times of day at which the device is set to act but also practically self-instructive without a set of operating directions and to the uninformed, as to how the time setting may be readjusted to suit the designs of the user, and it is a particular aim to render so plainly visible and unmistakable the spread of time during which the cooking or other desired operation shall take place both as to its duration and as to the times of day the cooking starts and stops that the device is so far as is possible, foolproof for the uninformed to operate.

A particular object of the present improvement is to make the time setting elements coact with the working parts of a simple, cheap but effective electric switch, snap-acting both in its movement to make and to break the circuit. A still further object is to provide as a unitary structure the clock face of whatever shape and marking together with the time setting means and the electric switch parts if same are employed, so that this unitary structure may be assembled with any form of standard clock movement whether of the spring motor type containing a chronometer escapement or of the many recently introduced forms of clocks driven, impelled, or wound by any form of electric motor. A further object is to avoid all limitation whatever as to the times of day or the minimum or maximum periods of time for which the device may be set it being the aim to when desired, annul the automatic action entirely by making a setting in which the "on" period is reduced to a minimum of zero and the "off" period is increased to a maximum of 360 degrees or vice versa. A further object is to arrange any electrically alive parts employed so that they are insulated from the handles to be grasped for adjusting the time setting and from any metallic parts of the clock movement.

To the above described ends and for other purposes which will appear from the following description my invention is better explained by an illustrative form thereof shown in the accompanying sheets of drawings, in which,

Fig. 1 is a front view, with an edge portion of the clock face broken away to expose the wiping switch contact finger and indicating in broken lines optionally usable means for adjusting the time setting parts.

Fig. 2 is a view taken in section through Fig. 1, 55

on the planes 2-2-2 indicating by broken lines the aligned relationship of time setting handles and further showing parts to represent any clock movement which may be employed together with electric wiring connections for the switch.

Fig. 3 is a segmental section on the plane 3-3 in Fig. 1 showing parts of the time setting and circuit switching mechanism.

Fig. 4 is an isometric view of the containing shell.

Fig. 5 is an isometric view of the time setting elements.

Fig. 6 is an isometric view of the friction disc and its spring pressed studs which retain the parts in Fig. 5 frictionally against the shell of Fig. 4.

Fig. 7 is an isometric view of the rotatable electric contact and its insulating facing.

Fig. 8 is an isometric view of the clock face or dial and the fixed bushing which holds the same.

Fig. 9 is an isometric view of the hour hand and the insulating arm integral with same which impels the contact member of Fig. 7.

Fig. 10 is an isometric view of the minute hand.

Fig. 11 is a diagrammatic illustration of two partially assembled intersliding split discs illustrating the idea underlying one possible form for the rotatably adjustable elements for setting the time for automatic actions with relation to each other and to the face of the clock.

Fig. 12 is a diagrammatic illustration of three spirally overlapping indicators or insulative or conductive switch tracks which may be employed for a purpose similar to that of the discs of Fig. 11 within the principles of this invention; a contact wiper circularly movable to ride on same being indicated by broken lines.

Fig. 13 shows three discs similar to the two of Fig. 11 removed from their normal concentric relation to show more clearly the nature of their assembly and sliding relationship.

Fig. 14 shows, disassembled, a conductive disc similar to the conductive disc of Fig. 5, but with overlapping annular ends.

Fig. 15 shows a similar construction of insulative disc.

Fig. 16 shows the discs of Figs. 14 and 15 in assembled relation at the extreme position of their relative adjustment when the front surface of the conductive disc is completely covered and concealed by the insulative disc.

Fig. 17 is a fragmentary sectional view similar to Fig. 3 with the discs of Figs. 14 and 15, relatively positioned as in Fig. 16, the lips 24' and 25' not being shown.

Fig. 18 shows the parts of Fig. 16 at their opposite extreme of relative adjustment wherein the front surface of the insulative disc is fully covered and concealed by the conductive disc.

Fig. 19 is a sectional view similar to Fig. 17 when the discs are relatively positioned as in Fig. 18, lips 24' and 25' likewise here being omitted.

In Figs. 1 and 2 there is indicated the frame 3 of any clock movement which may afford bearing for the minute spindle 10 or for some clock impelled spindle to be coupled to same and driven by the gear 4, the source of power and the time keeping mechanism not being shown in detail because a spring motor movement, an electric clock movement or any other form of movement may be used. The minute spindle 10 may be surrounded by a rotatable hub 11 for the hour hand of the clock suitably intergeared to spindle 10 by gears 5, 6, 7 and 8 in the well known manner

not necessary here to describe in detail so that the spindle 10 for the minute hand 12 makes twelve complete revolutions for each single revolution of the hub 11. It will be understood that the minute hand 12 is not essential to the present improvement since it is possible to tell time by the hour hand only and the latter could be directly impelled at proper speed by the clock movement without the intermediary minute spindle 10. The speed of hour hand 11 may be different from one revolution in twelve hours with time graduations to accord.

The structure of my present improvement may be disposed and mounted quite separately from the minute spindle 10 and hour hub 11 but is designed to carry the face of the clock here shown as the disc 13 which may or may not be circular in shape and which is fixed to the stationary hub 14 extending rearwardly and which may conveniently surround the rotatable hour hub 11 and may or may not afford bearing for same. In some cases it may be desirable to provide an insulating sleeve 15 to prevent metallic contact of the hour hub 11 with the hub 14 of the clock face.

At the rear end of the hub 14 and fixedly spaced from the clock face 13 by a collar 16 I may mount a large plate 17 of insulating material secured fast to the hub 14 by the nut 18 having threaded engagement with hub 14, and by the use of keys, pins, flats, solder or the like I may keep all these parts 13, 14, 16, 17 and 18 in fixed rotative relation and supported rigidly by any suitable mounting of the insulating plate 17 as by two or more brackets 9 upon the frame work 3 or within the casing of whatever kind of clock movement is employed and from which all these parts will consequently be insulated.

On the insulating plate 17 I may also mount the shell 19 which is a shallow dish shaped element shown in Fig. 4 having no permanent electrical connection with the above mentioned metallic parts which are fast with the clock face. Seated in the shell 19 I may arrange two or more inter-sliding annular portions of radially split discs shown most clearly in Figs. 5, 11 or 13. For the purposes of my invention it may be the function of these time setting split discs to afford contrasting colors in their portions which are visible as an annual ring peripherally exterior to the clock face 13. Or I may form one of these discs 20 of conductive material and the other disc 21 of insulating material so that they will divide the 360 degrees of a complete circle into two sectors one of which will afford a conductive track and the other an insulating track for a contact wiper or wipers to be described.

Fig. 11 shows the geometrical nature of each of the discs 20 and 21 and the manner in which they interslide when being assembled although when completely assembled for operation it will be understood that these discs are concentric. Also as shown in Figs. 14 to 19, inclusive the lips of each disc at the split may be elongated so that the two lips of a single disc overlap instead of being separated by an actual break as in the figures. The conductive disc 20 may be shifted rotatively by the handle 22 and the insulating disc 21 may be shifted rotatively by the handle 23 each handle being preferably of insulating material. It will be seen from the broken line showing of handle 23 in Fig. 2 and from Figs. 14 to 19, inclusive that the handles would not interfere with each other when passing or in alignment so that, if desired, the radial lips of these two

discs which occur at the point where they are split could be adjusted to a point of relative alignment with each other whereby either of the discs would cover up and expose no part of the adjacent face of the other disc. I give these discs preferably a peripheral bearing against the outer wall of the shell 19 and a sufficiently large opening in the center to keep them remote from the collar 16 although in some constructions I 5 may prefer to have them turn about an insulating bearing centered by the hub 14. Fig. 5 shows each disc provided with a raised lip or incline, 24 on disc 20 and 25 on disc 21 for coaction with a spring contact finger 26 to make a quick make 10 and break action which will now be described, although the provision of the lip 24, or its equivalent, on conductive disc 20, is alone adequate without the lip 25 on insulative disc 21 to effect the desirable amount of circuit breaking separation 15 between the rotative contact finger 26 and the conductive material of disc 20 when the circuit breaking snap action of finger 26 takes place.

This finger will be seen to be formed as a struck down portion 26 of a rotatable contact disc 27 and made of some springy conductive material such as phosphor bronze, this disc in all parts other than its portion 26 being backed up by an insulating facing 28 which carries in diametrically opposite relation to the contact finger 26 a similarly shaped spring finger 29 which however is not in conductive relation to the disc 27 but serves to equalize the spring pressure of the contact finger 26 to somewhat prevent the slanting or tipping out of true transaxial alignment of the disc 27 as a whole. An alternative construction is to make the contact fingers 26 and 29 rigid instead of flexible and provide an axially acting spring to yieldingly thrust the disc 27 rearward as a whole while permitting its rotation in electrical contact with the clock dial 13. The disc 27 further carries at its periphery the bent over projecting fork 30 which reaches forwardly over the edge of the clock face 13 to be engaged by the hour hand structure 31 and thereby impelled in unison with the rotation of the hour hub 11.

I may form this hour hand structure with an arm part 32 tapering into a projection suitable to engage the fork 30 and made of insulating and preferably of transparent material diametrically opposite to which the hour hand 33 may be provided as the conventional sheet metal pointer fixed to this transparent and insulating arm portion 32. The entire structure 31 may be fixedly mounted on the forward end of the hub 11 rather than frictionally mounted, in order to insure a positive impelling of the switch rotor contact disc 27 in addition to the mere time telling function of the hour hand as in an ordinary clock.

As regards the possible form of construction 60 above described which is but one of a large possible number of constructions subject to the broad principles of this invention, there remains to be mentioned merely the provision of binding posts for two electric wires 39 and 39' the circuit 65 through which is to be made and broken. One of these binding posts is represented by the screw 34 carried by the bracket 35 in electrical contact with the nut 18, hub 14 and clock face 13 and the other binding post is represented by the screw 36 70 carried by the bracket 37 which is in electrical contact with the shell 19 and thereby with the time setting conductive disc 20 at all times as insured by the contactor strip 38 carried by the forward standing part of the handle 22 which 75 wipes internally against the rim of shell 19. It

will be plain that even without this wiper strip 38 electrical contact between shell 19 and disc 20 is pretty well insured by the contact between the front face of the former and rear face of such portion of the latter as is not separated from the shell 19 by the insulation disc 21.

In operation, the contact disc 27 remains pressed by its contact finger 26 and by the other spring finger 29 insulated therefrom, forwardly against the metal of the clock face dial 13 with a light friction insuring the disc 27 remaining always in electrical contact with the clock face dial and thereby through hub 14, bracket 35 and screw 34 with one of the circuit wires 39. The circuit can be completed 15 with the other circuit wire 39' only when the contact finger 26 rests against the conductive disc 20 which in the setting shown in Fig. 1 can occur only between the hours of four o'clock and six o'clock. It will be observed that the 20 hour hand aligns radially with the circuit making and breaking terminal of this finger 26 the latter being in back of the clock face and the former being in front of the clock face. If desired the clock face could be made of transparent 25 material to render the action of this contact finger 26 visible to the user.

From Fig. 3 it will be apparent that a quick make and a quick break of the circuit is produced by the sudden dropping off of the contact finger 26 from the tips of inclines 25 and 24 and that when the setting discs are formed and used like parts 20' and 21' in Figs. 14 to 19 inclusive, there is possible advantage in omitting the raised step 25 on disc 21 so that contact finger 26 will travel through a greater distance in snapping from conductive disc 20 to insulative disc 21, thereby increasing the amount of its circuit breaking separation from the material of conductive disc 20. The correspondingly smaller distance that finger 26 will travel in snapping from insulative disc 21 to conductive disc 20 (because of the absence of a raised step such as 25 on disc 21) is of relatively small importance because in this action there 45 is no arc to be broken even if there be considerable voltage in the circuit to be controlled. If desired these inclines may be formed by merely striking up a portion of the discs 20 and 21 preferably to slope about in accordance with 50 the slope of the contact finger 26 and it will be seen that a projection 40 in Fig. 3 carried by one underlip of the insulating disc 21 prevents the relative rotation of this disc in relation to the conductive disc 20 beyond the point of approximate 55 radial alignment of their split sections so that they cannot be fully disengaged one from the other. Suitable stop means may be employed to limit the relative rotative adjustment of the discs in both directions, and one form which 60 such stop means may take is comprised in the engagement of the operating arm of one disc with the terminal lip of the other disc. Whatever stop means are employed may to advantage be so arranged that the terminal lips, or the 65 edges of inclines 24 and 25 if present, can be aligned with each other for which purpose it is desirable to have the two edges of each of the two discs overlap somewhat as illustrated in Figs. 14 to 19 inclusive. This overlapping will preserve 70 the inter-sliding engagement of each disc with the other both in the position indicated in Fig. 16 where the insulative disc completely covers and conceals the conductive disc and in the position shown in Fig. 18 where the conductive disc 75

3

completely covers and conceals the insulative disc thus making the circular track for contact finger 36 all insulative or all conductive at will whereby the circuit will continue respectively 5 opened or closed throughout repeated revolutions of contact finger 36. A contrast in coloring of the two discs so that one is recognizable as insulation and the other as a metallic conductive path would provide a logical and self informative indicator to the uninformed user as to during 10 what portion of the time represented by the dial the current to the electric range will be "On" and as to what proportion of the time represented by the dial it will be "Off". This ease of understanding would be even further increased by the use of simple wording "Cooking stops at this time" or "Cooking starts" together with an arrow pointing toward the graduation on the clock face as suggested in Fig. 1. Each disc 20 and 21 is individually adjustable to any position of adjustment both in relation to the other disc and to the face of the clock, and accurately so through the registering of the lip of each disc at its split portion with the graduations 15 at the edge of the clock face. The latter is of sufficient diameter as shown in the drawings to give an accuracy of time setting of better than five minutes which possible accuracy of setting is indefinitely increased if the diameter of the face of the clock is made larger.

The discs 20 and 21 will remain positioned wherever set by the friction imparted to them by the insulating washer 41 which is forced rearwardly by the tension of the leaf springs 43 exerted preferably upon three or more studs 42 20 extending rearwardly through holes in the insulating plate 11, the washer 41 preferably not rotating but permitting the discs 20 and 21 to be rotatively adjusted thereunder. As shown 25 herein washer 41 has a square hole axially slideable on a square portion of collar 16.

It may be mentioned that whereas my invention is not confined to such feature, it is desirable for some purposes that each of the separable 30 edges or lips of discs 20 and 20' and 21 or 21' should possess a substantially equal degree of yielding to admit the continuous portion of the other disc or ring thereby to permit a substantially equal angle of helical deflection in the continuous portions of both rings where they pass 35 through the separable edges of the other ring. This condition affords the smallest possible declination of each ring from a plane perpendicular to the axis about which the rings are rotatably 40 adjustable and thereby makes possible a minimum overall thickness of the assembled rings as well as uniform steepness to the inclines on each ring leading up to the drop-off points for contact 45 rotor 26.

While as pictured in the drawings and above 50 described the time setting elements 20 and 21 are shown as only two at inter-sliding disc-like members it is within the scope of the principles 55 of this invention to make them three or more in number and similarly intersliding as per Fig. 13. Such time setting discs could be merely indicators of the three different time settings and possibly of three contrasting colors for this purpose or could comprise electrically conductive 60 tracks to two or more different circuits. It is optional to form such multiple indicators or conductive and insulative tracks as spirally inter-sliding bands an edgewise view of which is indicated diagrammatically in Fig. 12 surrounding 65 70 which can rotate an electrical contact wiper in-

dicated in broken lines, as comprising a rotor 27' propelling or carrying the electric contact wiper 28' in conductive engagement first with one and then the others of the three spirally inter-threaded electrical conductive tracks 20'. These 75 three tracks are not in electrical connection with one another but may be constructed to comprise the terminals, respectively of three separate electric circuits and to be individually adjustable by the handle-like tabs 22' to set them into desired 80 relative and absolute positions for pre-determining the time of circuit-making and breaking actions which will result from rotation of the wiper 26'. One or more of the tracks 20' might be made of insulation rather than conductive material 85 depending upon the nature of the circuit switching actions desired.

It has been stated hereinbefore that the discs 20 and 21 need not comprise nor co-act with parts of an electric switch but they may instead serve as the time setting instrumentalities to position automatic actuating cams such as parts 40 and 41 of my co-pending application Serial No. 616,549 or such as cams 20 and 21 of my co-pending application Serial No. 642,496 or such 90 as cams 20 and 21 of my U. S. Patent Number 1,929,455 issued October 10, 1933 as well as similar cams in others of my co-pending applications and issued patents, or the positioning of the discs 20 and 21 herein can be made to set the time at 95 which any form of escapement or automatic action shall take place to secure the advantages of this invention residing merely in the provision of visible time determining indicators in alignment with the time markings on a dial or clock face.

I do not limit the invention to the manner of setting the discs 20 and 21 by simple handles such as 22 and 23 herein but may set them through the twisting of thumb knobs indicated 100 by broken lines as 44 and 45 in Fig. 1 respectively turning by means of spindles 48 and 49, the pinions 46 and 47 each of which may be in mesh with gear teeth which may be provided at the peripheral edges of disc 20 and disc 21, suitable 105 openings in the shell 19 permitting this mesh.

Brackets 50 and 51 extending from the shell 19 might afford bearing for the spindles 48 and 49. This provision of gear and pinion adjustment of the circular positions of discs 21 and 50 20 would be useful if it were desired to enclose the entire structure of this invention back of a glass window in a clock case, because handles such as 22 and 23 would require opening of the 55 glass to afford access or would require circular slots in the clock case out of which to protrude and which slots would give undesired entrance to dust and dirt.

As modifications I may prefer to form either the shell 19 or the discs of Fig. 5 as a dish with 60 conical rim after the manner of the ordinary decorative bezel or frame around a circular clock face. Obviously I may provide a thumb nut 52 by which to set the hands of the clock either at the front or at the rear as indicated by Fig. 2 65 and for this purpose slippage may be introduced between the spindle 10 and the gear 4 to constitute a friction drive. Many other modifications will occur to one experienced in the art and the 70 following claims are to include all equivalents of the construction which I have disclosed.

What I claim is:

1. Means for predetermining the time at which a succession of automatic actions shall occur including in combination, a circular scale of time 75

indicating graduations, annular indicator members of relatively contrasting appearance, each member being of at least 360 degrees circular extent and broken at one point to interrupt its 5 circular continuity and each of said members being arranged to pass helically through the break in the other member to permit relative rotative adjustment of the members, and a separate handle carried by each indicator member 10 for manually shifting the rotative relationship of said members, said handles being formed with a portion of each handle axially disposed and so positioned as to permit the passing of said handles for effecting the relative rotative adjustment of said members through at least 360 degrees of relative movement.

2. In combination, a plurality of intersliding indicator rings of respectively contrasting colors, each ring having a split through which the other 20 ring may helically pass to permit relative rotative adjustment of the rings and to mark a dividing line between the visible portions of the rings whereby each of said rings may be adjusted to expose or conceal any desired circular extent of 25 the other ring, a stationary clock face with time telling hands and positioned centrally of said indicator rings thereby to appear from the front as surrounded in part by the color of respectively different rings, said rings being also adjustable relative to said stationary clock face whereby any selected portion of the full periphery of said clock face may be made to appear as bordered by the color of either of said rings through suitable 30 relative and absolute adjustment of the rings, 35 a clock movement connected to impel the time telling hands, and electric current switching means connected in part to be motivated by said clock movement and in part operatively associated with said indicator rings in a way to 40 perform a current switching action when one of the clock hands and said dividing line between the visible portions of the indicator rings are substantially in radial alignment with each other and register with a common point on said clock 45 face.

3. In timing mechanism, in combination, a clock works, a frame to support said clock works, a bearing bushing rigid with said frame and extending forwardly therefrom, a clock face supported rigidly at the forward end of said bushing and centered thereon, a spindle driven by said clock works and extending forwardly through said bearing bushing, and a clock hand carried by said spindle to sweep in front of said clock 50 face, and means to indicate the division of said clock face into component segments, including discs of relatively contrasting appearance mounted to be relatively and absolutely adjustable about said bearing bushing at the rear of said clock 55 face.

4. In timing mechanism, a mechanical graph device for indicating the division of a circuitous series of dial graduations into a plurality of component groups, and including in combination 60 with said graduations, a plurality of inter-sliding indicator rings of relatively contrasting colors, each ring having a split disposed to register visibly with graduations on said dial and through which the other ring may helically pass whereby 65 either ring may be adjusted from a position exposing the full circular extent of the other ring to a position concealing the full circular extent of said other ring, and stop means arranged to limit the relative movement of said rings in one 70 rotative direction when either ring is so positioned

relative to the other ring that it exposes or conceals the entire circular extent of said other ring.

5. A time switch for assemblage with the works of a clock to be motivated thereby and formed as an integral structure separate from the works of the clock and carrying the clock face, a quick make and break switching mechanism at the rear of the clock face and a switch actuator rotatable at the rear of the clock face and having a part 10 extending forwardly to bridge the edge of the clock face thereby to be engaged and propelled by one of the hands of the clock works.

6. In combination with the hands and face of a clock a spindle to rotate one of said hands by 15 means of the clock work, a mechanism to be acted upon by the rotation of said spindle, and an arm carried by said spindle in front of the clock face for actuating said mechanism, said arm being of transparent material to avoid rendering 20 invisible any part of said clock face and a visible marker on said transparent arm simulating the time telling hand of a clock.

7. In a time switch, time setting means embodying in combination with a clock dial and 25 time telling hands mounted to sweep in front of same, a contact rotor to be impelled by timing mechanism at the rear of said dial, a circular track for said rotor also at the rear of said dial and comprised of alternately conductive and 30 insulative portions, each of said portions being individually adjustable as to its circular extent and as to its circular position with relation to said clock dial, the material of which said track is made extending to a greater diameter than 35 said dial thereby to be visible as a setting indicator back of and adjacent to the periphery of said dial.

8. In the structure defined in claim 7 the combination with the conductive and insulative portions of said track of a ratchet-like step carried 40 at the dividing line between each of the said portions of the track whereby the said contact rotor is projected with a quick snap action from a conductive portion of the track onto an insula- 45 tive portion of the track and vice versa.

9. In combination, a plurality of intersliding indicator rings of respectively contrasting colors, each ring having a split through which the other ring may helically pass to permit relative rotative 50 adjustment of the rings whereby each of said rings may be adjusted to expose or conceal any desired circular extent of the other ring, a stationary clock face with time telling hands positioned in front of and central of said indicator rings there- 55 by to appear from the front as surrounded in different parts by the color of respectively different rings, said rings being also adjustable relative to said stationary clock face whereby any selected portion of the full periphery of said clock face 60 may be made to appear as bordered by the color of either of said rings through suitable relative and absolute adjustment of the rings.

10. Means for predetermining the times at which a succession of automatic current switching 65 actions shall occur including in combination with timing mechanism and a current distributing rotor impelled thereby, a circular scale of time indicating graduations, annular indicating members of relatively contrasting appearance, each 70 member being of at least 360 degrees circular extent and containing a break permitting the helical entrance of the other member therethrough, and drop off steps arranged respectively at the break in each member to be traversed by said rotor 75

and departed from by said rotor with a snap action, the arrangement further being such that each member may be adjusted to a position relative to the other member wherein its said drop off 5 step acts as a baffle to preclude contact between said rotor and the other drop off step during a plurality of revolutions of said rotor.

11. In combination, a timing mechanism, circuit controlling mechanism operated by said timing mechanism, a plurality of arcuate markers of 10 relatively contrasting appearance, a clock face of smaller diameter than said arcuate markers and disposed centrally thereof so that its peripheral edge shall appear from the front as bordered in 15 part by one of said markers and in part by another of said markers, said markers being also adjustable relative to said clock face so that any selected portion of the entire circular edge of said clock face may be bordered by either of said arcuate markers alone, and connections causing the 20 functions of said circuit controlling mechanism to occur at times of day indicated by the position of said markers against said clock face.

12. In a time switch, means for selectively varying and determining more than two different intervals of time to elapse between successive current switching actions of the time switch comprising in combination, a time movement, a contact wiper connected to be impelled in a circular path 25 by said movement, more than two circularly interlapping ring devices each device having a break through which a plurality of the other devices may 30 rotatively slide, a plurality of circular tracks of conductive material carried by respectively different ones of said ring devices and presented thereby in the path of said contact wiper, whereby relative rotative adjustment of said interlapping ring devices varies and predetermines what circular extents of more than two of said devices and 35 of a plurality of said conductive tracks shall be contacted by said wiper in its circular travel.

13. In combination, a plurality of overlapping members, exposed portions of which lie in different concentric circles thereby to be utilized for respectively different purposes, a current switching rotor mounted to sweep in contact with said members upon a circle of relatively small diameter, and a time dial stationed in front of said members and of sufficient diameter to conceal that portion of 45 said members comprised within the said circle of small diameter, whereby portions of said members in circles of larger diameter than said dial may appear to surround said dial and thereby serve as indicators of the circular positions of 50 said members.

14. In timing mechanism, in combination, a clock works, a frame to support said clock works, a bearing bushing rigid with said frame and extending forwardly from the plane of said clock 55 works, a clock face supported rigidly at the forward end of said bushing and centered thereon, a spindle driven by said clock works and extending forwardly through said bearing bushing, a clock hand carried by said spindle to sweep in front of 60 said clock face, and means to indicate the division of said clock face into component circular parts, including discs of relatively contrasting appearance mounted to be relatively and absolutely adjustable about said bearing bushing back of said 65 clock face and of larger area than said clock face, whereby said clock face appears to be completely surrounded by a background composed of the visible 70 portions of said discs.

15. In a time switch, a stationary clock dial, 75 clock hands pivoted concentrically therewith to

sweep in front of said dial; a circuit controlling rotor connected to move when said clock hands move and pivoted concentrically with said clock dial at the rear thereof to be concealed thereby, adjustable contact controlling members rotatably mounted at the rear of said dial, concentric therewith and concealed thereby and co-operating with said rotor to determine the time of day that automatic switching action shall take place, and indicators movable at the rear of said dial and appearing in part at the edge thereof when said dial is viewed from the front and connected respectively to said contact controlling members, thereby to show by the position of their visible portions about the edge of the clock dial, the times of day 15 that automatic switching actions will take place.

16. In combination, a clock face, clock hands pivoted to sweep in front of said face to tell the time of day, a circular indicator ring of at least 20 360 degrees extent disposed to appear from the front of said clock face as surrounding the same, means arranged for adjustive sliding movement in circular relation to said ring in both circular directions and reversibly slidable from all positions relative thereto for selectively concealing 25 or exposing any portion or the whole of the full circular extent of said ring thereby to provide a boundary mark for the visible portion of said ring, said ring being turnable to station its thus exposed portion at any one of an unlimited number of positions about said clock face, a clock movement connected to impel the time telling hands, and electric current switching means connected in part to be motivated by said clock movement and in part operatively associated 30 with said indicator ring and means arranged for adjustive sliding movement in a way to perform a current switching action when one of the clock hands and said boundary mark for the visible portion of the indicator ring are substantially in 35 radial alignment with each other and register with a common point on said clock face.

17. In combination, a time dial, an indicator ring of at least 360 degrees circular extent concentric with said dial, means selectively adjustable to conceal any portion or the whole of the full circular extent of said indicator ring, said ring being turnable relative to said dial to station its exposed portion at any of an unlimited number of positions relative to said dial, and said 50 ring being of larger diameter than said dial, and disposed at the rear of said dial to be visible around the periphery of the dial when viewed from the front of the dial.

18. In timing mechanism, in combination, a 55 clock works, a frame to support said clock works, a bearing bushing rigid with said frame and extending forwardly from the plane of said clock works, a clock face supported rigidly at the forward end of said bushing and centered thereon, a spindle driven by said clock works and extending forwardly through said bearing bushing, a clock hand carried by said spindle to sweep in front of said clock face, and circuit switching means including a circuit controlling rotor rotatable about said bearing bushing back of the clock face and connected to be impelled by said clock works, and discs to determine the time said rotor shall act to switch a current, rotatively adjustable about said bearing bushing also in back 60 of said clock face, in which arrangement said discs but not said rotor are visible outside the area occupied by said clock face when said timing mechanism is viewed from the front.

19. In combination, a clock works to furnish 75

power, a clock dial, circuit making and breaking means positioned in back of said clock dial and concealed thereby, means rotatable by the power of said clock works to be visible in front of said clock dial for telling time, and connections between the former means and the latter means whereby said latter means impels said former means while the two means are on respectively opposite sides of said dial, said connections straddling the edge of said dial.

20. Means for indicating the division of a stationary 12-hour clock face into selective fractional portions whose sum shall comprise the full circular extent of said clock face, including in combination with a clock face, graduations proximate the edge thereof, two rotatively adjustable elements each of at least 360 degrees circular extent and of greater diameter than said clock face and disposed at the rear thereof to be visible from the front around the periphery of said clock face, time telling hands rotatable in front of said clock face, and means rendering said elements so adjustable as to selectively conceal or expose the entire circular extent or any selective fractional part of the entire circular extent of either element, whereby the elements may be adjusted to cause the clock face to appear as surrounded entirely by one of said elements or to appear as surrounded entirely by the other of said elements or to appear as surrounded entirely by a combination of the two elements in arcuately end-to-end relation.

21. In combination, a plurality of intersliding indicator rings of respectively contrasting colors, each ring having a split through which the other ring may helically pass to permit relative rotative adjustment of the rings and to mark a dividing line between the visible portions of the rings whereby each of said rings may be adjusted to expose or conceal selective arcuate extents of the other ring, a stationary clock face, and time telling hands mounted to sweep in front of said face, said face covering an incomplete area in front of said rings thereby to expose the color of each of said rings that is exposed by the position of the other ring as viewed from the front of said clock face, a clock movement connected to impel the time telling hands, and electric current switching means connected in part to be motivated by said clock movement and in part operatively associated with said indicator rings in a way to perform a current switching action when one of the clock hands and said dividing line between the visible portions of the indicator rings are substantially in radial alignment with each other and register with a common point on said clock face.

22. In combination with concentric minute and hour spindles of a time telling clock, a time motor connected at the rear ends of said spindles to rotate the spindles, minute and hour hands carried respectively on the front ends of said spindles, a stationary clock dial with time graduations disposed immediately back of said hour hand, and circuit controlling means connected

to be motivated by said time motor and disposed in back of said dial so as to be concealed thereby from the sight of an observer of said clock hands and time graduations, and a time setting indicator operatively associated with said circuit controlling means and disposed for appearance at the edge of said dial and mounted to be rotatively adjustable in relation to the time graduations thereon whereby the time of day and the time setting of said means may be simultaneously viewed from the front of said clock dial.

23. An assemblage of parts of a time telling clock with parts of a selectively settable time switch, characterized by compact and concentric relationship of parts and including in combination, concentric minute and hour spindles, minute and hour hands carried respectively on the forward ends of said spindles, a time motor at the rear end of said spindles connected to impel the latter, circuit controlling means disposed and operating about the axis of said spindles by power derived from said motor and including normally stationary means co-operating with said power driven means to make and break a circuit and carrying an arcuate indicator to show the position of said stationary means, and a stationary clock dial supported intermediate said clock hands and said circuit controlling means and of a size to expose said arcuate indicator circularly exterior to the dial edge while concealing the other parts of said circuit controlling means.

24. Indicators for dividing a circle into graphically visible parts comprising in combination, a split ring of substantially 360 degrees circular extent and of flexible material to be disaligned at its split portion, a second split ring of appearance to contrast with the first said ring and likewise of substantially 360 degrees circular extent, means to mount said rings so that each ring may pass through the split portion of the other ring thereby to dispose extents of its circular length on respectively opposite sides of the other ring varying from 360 degrees circular extent to entire absence of said extent and means to selectively adjust said rings both relatively and absolutely by rotative movement of one or both rings.

25. In combination with a minute spindle and concentric hour spindle of a time telling clock, a motor of time keeping speed connected to rotate said spindle, an hour hand rotated by said hour spindle and a minute hand rotated by said minute spindle for telling the time of day, a clock dial with time-of-day markings disposed to be stationary in back of said hour hand and minute hand, and circuit controlling means operated by said motor and disposed immediately back of said clock dial to be concealed thereby from the sight of an observer of said clock hands, and time setting indicators for said means mounted to be visible at the peripheral edge of said clock dial thereby to be exposed to the sight of an observer of said clock hands.

RAYMOND D. SMITH. 65
